Primary Examiner — Elizabeth J Oswecki

(57) **CLAIM**

The ornamental design for a donation box, as shown and described.

DESCRIPTION

FIG. 1 is a front perspective view of a first embodiment of a donation box, showing my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof.

FIG. 7 is a right side elevational view thereof.

FIG. 8 is a front perspective view of a second embodiment of a donation box, showing my new design.

FIG. 9 is a front elevational view thereof.

FIG. 10 is a rear elevational view thereof.

FIG. 11 is a top plan view thereof.

FIG. 12 is a bottom plan view thereof.

FIG. 13 is a left side elevational view thereof; and,

FIG. 14 is a right side elevational view thereof.

The broken lines in the drawings illustrate environmental structure and form no part of the claim.

1 Claim, 14 Drawing Sheets
